UNITED STATES PATENT OFFICE.

SHERIDAN A. WALKER, OF NEW YORK, N. Y., ASSIGNOR TO THE CARSON COMPANY, OF CHICAGO, ILLINOIS, A CORPORATION OF ILLINOIS.

CAR-SEAT CONSTRUCTION.

1,301,019.

Specification of Letters Patent. Patented Apr. 15, 1919.

Application filed July 9, 1918. Serial No. 244,066.

To all whom it may concern:

Be it known that I, SHERIDAN A. WALKER, a citizen of the United States, residing at New York, in the county of New York and 5 State of New York, have invented certain new and useful Improvements in Car-Seat Constructions, of which the following is a specification.

The present invention relates to the construction and arrangement of certain portions of a car seat such as is commonly employed in railway passenger coaches, etc., and deals particularly with certain portions of the mechanism comprising the means for 15 permitting the back of the seat to assume a reverse position with respect to the cushion.

The objects of the invention are to provide members in the form of rods, which rods will be of the character of a crank and will serve 20 the double function of connecting the mechanism on the wall and aisle sides of the seat, so that one side of the back will not move in advance of the other, which would cause a binding; and to also utilize these rods as an 25 actuating means for the rocker plates.

A further object of the invention is to provide a connection between these rods and certain links connected to the back, which will be of a freely detachable character, 30 eliminating the use of bolts and other similar securing means now employed for connecting such parts, which expedites their assembly.

A further object of the invention is to provide 35 a bearing for these links in the rocker plate, thus insuring a connection between these plates which will not become loose and thereby result in a loose and improper movement on the part of the back.

40 A further object of the invention is to provide a simple means for journaling the connecting rods to maintain them in proper relation to the links.

The invention further consists in the 45 features of construction and combination of parts hereinafter described and claimed.

In the drawings:

Figure 1 is a side view of a car seat made 50 in accordance with the present invention;

Fig. 2 is a front view of one end of said seat;

Fig. 3 is a detail showing one of the side plates and connections thereto;

Fig. 4 is a section on line 4—4 of Fig. 3, 55 looking in the direction of the arrow;

Fig. 5 is a sectional detail showing the connection between one of the links and one of the side plates; and

Fig. 6 is a detail section on line 6—6 of Fig. 3.

In the art to which the present invention relates, car seats are constructed with movable backs, which can be swung from one edge of the seat cushion to the other, thus reversing the position of the seat in accordance with the direction of movement of the car. In such constructions, it has been customary to form a connection between the parts which enables the back to be moved, and whereby all portions of the back will move in unison, so that no matter whether the force for moving the back be applied to the back at the aisle side thereof or the wall side thereof, a free and easy movement will always be maintained.

It has been customary to join this connection to the other portions of the mechanism by means of bolts, nuts, or similar attaching devices. This, however, is a difficult operation, requiring considerable exactitude in getting the various openings in line, so that the bolts can readily be inserted and the parts properly assembled.

It has also been customary to attach supplemental parts to this connection means for the purpose of actuating the rocker plates. A loosening of the connections in any respect creates a lost motion in the back and makes it wobble, which is highly undesirable.

The present invention is an improvement 90 on the seat constructions, with a view of simplifying and bettering the portions thereof above referred to.

Referring now to the drawings, the device is shown in conjunction with a car seat 7, 95 comprising a back 8, arms 9 and a cushion 10, all of which may be of any suitable and desired construction. At the aisle end of the appliance, a plate 11 is employed, secured by suitable fastening means 12 to the arm; and at the opposite end of the seat is a similar plate (not shown) attached to the wall of the car, which constitutes the wall plate. The use of the foregoing plates is well known in car seat constructions.

Both at the wall and aisle sides of the seat are rocker plates 13 for the purpose of changing the angular disposition of the cushion when the back is moved. The use of these rocker plates is well known, and al-

though the particular plate shown in the drawings is deemed to be new and novel, it does not have any bearing upon the subject matter of the present invention and will not 5 be described in detail.

The seat is supported on the aisle side by a suitable standard 14, as is usual; and the seat is further equipped with a foot rest 15, which may be of any suitable construction. 10 Formed in the rocker plates are vertical slots 16, and extending through these slots are rods 17, which form a portion of the subject matter of the present invention.

These rods extend from side to side of the 15 seat and are formed with an offset 18 located just outside of the rocker plates, as will be understood from Fig. 6, although the offsets may be placed a greater or less distance from the rocker plates if desired.

20 The rods are further formed with a bend 19 and a bend 20 adjacent their ends; and the portion 21 lying between said bends is, in the construction shown, of flattened formation, the function of which will herein- 25 after appear. The rods terminate in an end 22, about which they turn.

Engaging with these rods are links 23, each of which is pivotally connected to a plate 24 joined to the seat back. The ends 30 of each of these links is in the form of a slotted lug 25, having a slot 26 therein, the walls of which overlie and engage the flattened portions 21 of the rods 17; and each 35 of the links is formed with a base 27 which is journaled in a recess 28 formed in the aisle or wall plates, depending upon whether the links on the wall or aisle side are referred to. By this construction, the slotted ends of the links act in the manner of a jaw 40 to engage with the rods in the manner of a wrench, so that when the links are moved, they will, by reason of their connection to the rods, turn the latter.

There is a similar arrangement of the 45 plates and links for both the wall and aisle sides of the seat, but since they both are exactly similar in nature, only a detailed disclosure of the aisle side has been set forth.

It will be understood from the drawings 50 and the foregoing description that the connection described between the links and rods is of a freely detachable character and does not require the use of bolts, rivets, or like fastening devices, for the purpose of securing them together, and thereby eliminates the necessity of the careful assembly operation which is required when bolts or similar devices are used for this purpose.

The rods 17, extending as they do from 60 the aisle plate to the wall plate of the car seat, form a connection between the operating parts on the aisle side and the operating parts on the wall side, so that such parts are moved completely in unison. Therefore, 65 when the pressure is applied to move the

back, it will make no difference whether the back is grasped at the wall or the aisle side, since the pressure will be transmitted to the opposite side through the medium of the rods 17; and the seat will move in a proper 70 manner to eliminate the binding or jamming which would occur if the aisle side moved ahead of the wall side, or vice versa. It is obvious that in such instances the back would assume a diagonal position, causing 75 a retardation of the free movement thereof.

Referring now to the lugs 25 on the links, which are slotted to provide jaws, it will be seen that these jaws contact and engage the portions 21 of the arms, and thus there is 80 provided an elongated surface connection between said lugs and the arms, so that the lugs have a firm and efficient grip upon the rods, which grippage is augmented by the flattening of the portions 21. When the 85 back is moved, one end of the link 23 is carried by the plate 24, and the other end of the link turns about its seat in the recess 28 in the end plate. The links in so turning about their mounting in said recess will 90 swing the jaws 25 and by the grippage of said jaws on the portion 21 of the rods 17, said rods will be turned.

These rods are offset as described, at 18, so that they are of crank formation, and 95 when turned, the portions 29 thereof, which lie in the slots 16 of the rocker plates, will exert a pressure against the walls of the slots 16, causing the plate to shift in accordance with the swinging of the back. 100 These rocker plates have to do with the changing of the angular disposition of the cushion, as is well known in the art.

The rods as thus formed perform the double function of a connecting part between the mechanism on the aisle and wall sides of the seat and constitute cranks for the purpose of causing a movement of the rocker plates. This simplifies and improves the construction and operation of the seat 110 mechanism over what, so far as I am aware, has existed in the prior art.

By forming the lugs with the boss 27 and journaling said boss directly in the end plates, a firm and efficient bearing is provided for the links, so that they do not become loose, causing a wobbly movement of the back, which is undesirable; and, moreover, the hollow boss 27 provides a journal bearing for the end 22 of the rods 17, thus 120 making a very simple and compact mounting for both the rods and the links.

Although the device has been described with considerable particularity, it is not deemed to be limited other than may be by 125 the terms of the appended claims.

I claim:

1. In a car seat, the combination of a movable back, a pivoted link connected to said back, said link being formed with a slot to 130

provide a jaw member thereon, a rod in the form of a crank, said jaw member engaging said rod to turn the same as the link is moved, a cushion, rocker mechanism for changing the angular position of the cushion as the back is moved, and a connection between said rod and rocker mechanism, substantially as described.

2. In a car seat, the combination of a movable back, a pivoted link connected to said back to permit movement thereof, a crank rod, an offset portion on said crank rod, a slotted jaw-like portion on the link engaging the offset portion on the rod, whereby the rod is turned as the link is moved, a cushion, rocker mechanism for changing the angle of the cushion as the back is moved, and a connection between said rod and said rocker mechanism, substantially as described.

3. In a car seat, the combination of a movable back, a pivoted link connected to said back to permit movement thereof, a crank rod, an offset flattened portion on said rod, a slotted jaw-like portion on said link engaging the offset portion on the rod, whereby the rod is rotated as the link is moved, a cushion, rocker mechanism for changing the angle of the cushion as the back is moved, and a connection between the rocker mechanism and rod, substantially as described.

4. In a car seat, the combination of a movable back, pivoted links connected to said back to permit movement thereof, a portion of said links being positioned upon each side 35 of the seat, a cushion, rocker mechanism for shifting the angle of the cushion as the back is moved, a rod in the form of a crank, each of said links being formed with a recess to receive an end of a rod, each of said rod 40 ends being configured to seat within the recess with a non-rotating fit, said non-rotating fit causing the link to act to turn the rod as the links are moved, and said rod when moved serving to actuate the rocker mechanism, substantially as described.

5. In a car seat, the combination of a movable back, pivoted links connected to said back to permit movement thereof, a portion of said links being positioned on each side of 50 the seat, a crank rod, each link being formed with a recess for receiving an end of a crank rod, a wall on said recess being of flat-faced formation, a complementary flat face on the rod end, and said flat faces coöperating to 55 turn the rod as the link is moved, a cushion, rocker mechanism for changing the angle of the cushion as the back is moved, and an operative connection between said rod and rocker mechanism, substantially as de- 60 scribed.

SHERIDAN A. WALKER.
